UNITED STATES PATENT OFFICE

2,414,802

COMBINED STOKER AND FURNACE

George H. Cushing, Chicago, Ill.

Application June 22, 1944, Serial No. 541,545

9 Claims. (Cl. 110—32)

1

This invention relates to a method of and apparatus for burning hard fuel and part of the subject matter thereof has been divided from my pending application for patent on an improvement in Coal stokers and control thereof and the like, filed February 6, 1943, under Serial No. 474,937, and is a continuation in part thereof.

One of the objects of this invention is the provision of a novel method for burning hard fuel, such as the various kinds of coal, coke, etc., whereby all of the combustibles in fuel may be entirely consumed, leaving only a residue of fine ash.

Another object is the provision of a method of burning hard fuel wherein fresh charges of the fuel are charged upon a cleared section of the grate and contiguous with a previous charge which has become ignited.

Another object is the provision of a method of burning hard fuel which consists in controlling the amount of the charges of fuel, the frequency of introducing the charges upon the grate, coordinated with damper means to regulate the draft in accordance with the frequency of charging the furnace, whereby a substantially constant temperature may be maintained in the space or spaces heated by the furnace, regardless of the outside temperature.

Another object of this invention is to provide a side feed stoker for use in connection with a furnace or other heating apparatus for burning hard fuel in measured quantities concurrently in predetermined stages of combustion.

Another object is to provide a stoker with automatic feed and automatic ash remover.

Another object is to provide a furnace capable of burning a great variety of sizes of solid fuel, either separately or mixed.

Another object is to provide a stoker which will free its operator from any manual attendance upon the furnace.

Another object is to provide a simple and comparatively inexpensive stoker construction not likely to get out of order.

With these and other objects and advantages in view, this invention consists in the several novel features hereinafter fully set forth and claimed.

Apparatus for carrying on the method is illustrated in the accompanying drawings, in which:

Fig. 1 is a view partly in plan and partly in horizontal section taken on the line 1—1 of Fig. 2 with the crank shaft 30 partly broken away;

Fig. 2 is a view partly in side elevation and

2

partly in vertical longitudinal section taken substantially along the line 2—2 of Fig. 1, with roller 75a shown in dotted lines to indicate its location;

Fig. 3 is an end elevation looking in the direction of the arrow 3 in Fig. 2;

Fig. 4 is a perspective view of fragments of the reservoir, fire box and ash conveyor, and illustrating a track for a certain trap door associated with the grate;

Fig. 5 is a front elevation of a control box seen in Fig. 2;

Fig. 6 is a vertical cross section taken on the line 6—6 of Fig. 5;

Fig. 7 is a horizontal section taken on the line 7—7 of Fig. 5;

Fig. 8 is a vertical section taken on the line 8—8 of Fig. 7;

Fig. 9 is a vertical section through fragments of a smoke pipe, illustrating the damper;

Fig. 10 is a plan of the damper seen in Fig. 9 with the smoke pipe shown in section;

Fig. 11 is an under plan of a fragment of one of the grate segments; and

Fig. 12 is a wiring diagram of a time switch used for controlling the starting and stopping of the motor which operates the stoker.

Referring to said drawings, which are somewhat schematic and illustrate one embodiment of the invention, the reference character 10 designates the casing of a furnace or other solid fuel burning heating apparatus, in the lower end of which is a low fire-brick wall 11 surrounded by a sheet metal retaining wall 11a.

Mounted upon a base plate 12, which extends 35 within and without the casing 10, is a base 13 upon which is secured a post 14 having an annular shoulder 15 upon which rests a beveled gear wheel 16 which carries a grate composed of grate sections 17 that are desirably of segmental form

40 and ride on a circular track 11b carried by the retaining wall 11'. Also mounted on the upper end of the post 14 is an air dome 18. The grate and fire-brick wall 11a provide a fire-box in which the fuel is consumed. The beveled gear wheel and grate are intermittently rotated in timed relation to the feeding of fuel upon the grate and the means for rotating the grate may comprise the beveled gear wheel 16 which meshes with a beveled pinion 20 mounted upon one end of a shaft 45 21 journaled in suitable bearings and intermittently rotated from the main drive shaft 30 of the apparatus by suitable gearing, as will be presently described.

50 Disposed at one side of the furnace is a fuel delivery conduit or reservoir 22 which is located

55

above the plane of the grate and is mounted upon suitable supports 23a which rest upon and are fastened to the base plate. One end of the reservoir opens to the interior of the fire-box through a throat 23. One side wall 24 of the reservoir extends in a radial direction from the fire-box, the opposite side wall 25 being suitably spaced therefrom to receive between said side walls a reciprocating ram or plunger 26 which functions to intermittently feed solid fuel into the fire-box and upon the grate and in an approximately radial direction with respect to the axis of the grate.

The bottom wall 27 of the reservoir projects over the edge portion of the grate and guides the fuel thereto. The top wall of the reservoir has an opening 29 therein located above and forward of the ram. Fuel entering said opening falls upon and in front of the ram where it lies until the ram is retracted, whereupon the fuel lying upon the ram falls into the reservoir in front of the front face of the ram. This space in the reservoir is calculated to hold a measured quantity of fuel sufficient for one charge besides a wall of fuel which always remains in the throat.

Any form of hopper or fuel feed may be employed to deliver fuel into the reservoir and the one illustrated will be hereinafter described.

Journaled in suitable bearing brackets 41a mounted on the base plate is the main drive shaft 30, here shown in the form of a crank shaft of which the crank 31 is connected to one end of a connecting rod 32, the other end of which is connected to the ram 26 by a wrist pin 33 secured in the side walls of the ram.

Mounted on a motor base 34, which rests on and is secured to the base plate 12, is a motor 35, desirably in the form of an electric motor, which comprises the prime mover for the apparatus. Associated with the motor is speed reducing gearing 36 which couples the motor shaft with the main drive shaft 30 and rotates the same through one or more complete revolutions during each cycle of operation of the stoker. Mounted adjacent the speed reducing gearing is a circuit breaker or time switch 37 which breaks the circuit for the motor at the completion of each cycle of operation.

The circuit breaker or time switch may be of the common and well known time switches controlled by a rotating shaft to break the circuit at the conclusion of a cycle of operation.

In Fig. 12, such a time switch 37 is shown, having a magnet 37a connected to the control means 40, 45, by lines 46, 65a. The associated armature 37b is connected to a movable switch contact piece 37c by a link 37d and makes contact with a stationary contact piece 37e whenever the magnet is energized as a result of one of the contact points 41 closing the circuit through the magnet. When the circuit through the conductors 37f, 37g to the motor 35 is closed by the contacts 37c and 37e, the motor is started. A latch 37h has a finger that prevents the movable contact 37c from breaking contact with the stationary contact 37e when the magnet 37a is de-energized as a result of the contact 41 running off the contacts 45. The latch 37h is connected to a release lever 37i by a link, and the main drive shaft 30 has a pin or stud 37j thereon, which engages the lever 37i when the shaft has made one complete revolution, thereby releasing the movable contact 37c from the latch and permitting it to be swung out of contact with the stationary contact 37e, thereby 75

opening the circuit through the conductors 37f, 37g and stopping the motor.

The control means for controlling the frequency of charging the furnace and for controlling the damper is best seen in Figs. 5 to 10 inclusive. This control means may be installed at any convenient place in the building heated by the furnace. In general, it comprises a cabinet 38 in which is mounted a motor 39, such as a clock works, upon the main drive shaft 38a of which is removably mounted a time disc 40 composed of non-conducting material and having concentric rows of contact points 41 secured therein with their ends flush with the side faces of the disc. 15 The contact points are spaced equidistantly in each row but the number of contact points in each row increases progressively outward from the center of the disc so that with a constant rate of speed of the disc a more or less number of contact pieces will pass a given point during each hour or day.

Slidably guided in a vertical guideway 42 secured to a side wall of the cabinet is a vertically movable contact carrying member 44 formed with 25 a forked arm 45 straddling the disc and containing two electrical conductors 46 which are provided with inturned contact fingers 47 adapted to make contact with the contact points 41 of any row. Means are provided for raising and lowering 30 the contact carrying member 44 so as to position the fingers to make contact with any given row of contact points, depending upon outside temperature, grade of coal, etc. The means here shown for this purpose comprise an upright rack bar 48 which extends up from the forked arm 45 and has rack teeth on one edge that mesh with a pinion 49 fast on a shaft or a spindle 50 that extends out through and is secured to a dial 51 which cooperates with a vernier 52 secured in 35 the front wall 38. A suitable bearing bracket 53 supports the shaft and a knob 54 is fastened on its outer extremity whereby it may be rotated. Rotation of the shaft will raise or lower the contact carrying member 44 through the instrumentality of the pinion and rack bar.

The contact carrying member 44 also controls the damper 55 which is contained in the smoke pipe 56 of the furnace. The damper consists of two substantially semi-circular damper plates 57 carried by two parallel rods 58 which are rotatably mounted in a split ring 59, clamped upon the two adjacent ends of two smoke pipe sections. On one end of the rods 58 are formed crank arms 60 that cross each other and incline upwardly 55 away from the damper plates when the latter occupy a horizontal position. Means are employed for holding the damper plates in any position of adjustment and, as shown, said means comprises a weighted body 61 which rests upon the upper extremities of the crank arms and is suspended by a cable or other flexible element 62 passing over sheaves 63, 64 and extending to the contact carrying member 44 where the cable is secured to said member. When the contact carrying member is lowered to increase the firing frequency it raises the weighted body 61, permitting the damper plates to swing down under the force of gravity, thereby enlarging the passageway between the damper plates and the smoke pipe.

In the operation of the control means just described, when the forked arm 45 is set to make contact with the outermost row of contacts, the weighted member 61 has been raised to the limit of its upward movement, thereby holding the

damper plates in their fully open position. In this position of the contact carrying member the contact fingers are arranged to make contact with the contact points in the outermost row containing the greatest number of contacts; and as a result, the circuit to the circuit breaker or time switch is closed frequently, thereby causing frequent charging of the furnace. In milder weather the contact carrying member is raised more or less by rotating the knob 54 in a clockwise direction thereby bringing the forked contact carrying arm 45 into a position in which the contact fingers contact with one or another of the inner rows of contact points, and simultaneously the weighted body 61 is lowered thereby 10 swinging the damper plates into a more or less horizontal position.

The electrical conductors 65a lead from the control cabinet through the circuit breaker or time switch 37 and are suitably connected to the house current. It is to be understood that, as the disc slowly revolves with the contact carrying member set to make contact between the contact fingers and the contact points of any row, as each contact point contacts the fingers, it closes 20 the circuit to the circuit breaker or time switch, thereby closing the circuit to the motor and setting it in motion. The circuit breaker or time switch is set to permit the motor to run for a sufficient length of time to rotate the drive shaft 30 30 through one or more complete revolutions of 360 degrees and then break the circuit and stop the motor.

It is to be understood that during each cycle of operation a measured charge of fuel is charged 35 into the fire box and upon the grate, which charge is deposited upon the grate contiguous with the previous charge of fuel which has already been ignited. Each charge of fuel assumes a "pie slice" form upon the grate and is ignited from the burning previously deposited charge. The grate and the fuel thereon remain stationary until the ram is being retracted, whereupon the grate is given a partial rotation whereby to 40 present a vacant space on the grate to receive a subsequent charge to be deposited contiguous with the last charge. The means for intermittently rotating the grate will now be described.

An accepted practice when coal is fired by hand has been for years to move the live coal to one side and fire the green coal on the vacated space. In addition to the standard practice, I have provided clearance space between the bottom of the partition and grate to permit small amounts of coked coal to pass beneath the partition to serve 45 as kindling. Finally the green coal impinges against the incandescent coal in the previously deposited charge and is ignited.

Mounted upon the shaft 30 is a mutilated gear wheel 65 which is arranged to mesh with a gear wheel 66 mounted upon a shaft 67 journaled in the bearing brackets 41a. Mounted upon shaft 67 is a beveled pinion 68 which meshes with a beveled pinion 69 mounted on the shaft 21. The mutilated gear wheel 65 has gear teeth upon 180 degrees of its face and is so related to the gear wheel 66 that when the main or crank shaft 30 begins its cycle of rotation and begins to project the ram 26, the gear wheel 66, shaft 21 and grate will remain idle, and that when the crank begins to retract the ram, the first tooth of the mutilated gear wheel 65 meshes with the gear wheel 66 and rotates it and therewith rotates the beveled pinions 68, 69, shaft 21, pinion 20 and gear wheel 16, thereby rotating the grate through a 50 60 65 70 75

predetermined arc of a circle. In the present disclosure the timing and gear ratio is such that the crank shaft rotates the grate through an arc of 30 degrees during each cycle of operation, thereby bringing an empty segment of the grate in front of the throat of the reservoir.

Rigidly secured to the side wall 24 of the reservoir is a partition or sweep 70 which extends radially over the grate to the air dome 18. The partition 70 extends down to the grate and it functions to sweep the ashes from the grate as they encounter the partition.

One of the grate segments is provided with a swingable trap door 71 located in a cutout portion of a grate section. The trap door has a roller 72 (see Fig. 4) which projects in a radial direction with respect to the axis of the grate and runs upon the annular track 11b. The track is offset downwardly as at 73 to permit the trap door to swing down and allow clinkers, slate and other unconsumed pieces to discharge from the grate.

Suitable fuel feed and ash removal apparatus are provided, one form of which is shown for the purposes of illustration.

Extending from a suitable fuel bin (not shown) is an inclined conveyor 75 which conveys fuel to the reservoir and discharges it through the opening 29 thereof. A cover or closure 76 is provided upon the reservoir above the opening 29. Any suitable driving means may be provided for the conveyor 75 and it is here shown as comprising a sprocket wheel 77 on the shaft 21, a sprocket wheel 79 on the shaft of the upper roller 75a over which the conveyor is trained, and a sprocket chain 78 trained over said sprocket wheels.

The ash removal means, as shown, comprises a conveyor belt 80 trained around rollers 81, 82, 83 carried by suitable brackets. The conveyor belt 80 is disposed below and at one side of the partition or sweep 70, as shown in Fig. 1, and a hopper 80a is provided below the grate for guiding the ashes to the conveyor belt. Suitable means are provided for driving the conveyor belt 80 and, as shown, said means comprise a belt 86 trained around a sheave 85 on the main crank shaft and a sheave 87 on the shaft of the roller 83.

Below the discharge end of the conveyor belt 80 is a transversely extending conveyor belt 84 which carries the ashes away from the furnace. Driving means are provided for the conveyor belt 84 and, as shown, said means comprise a gear wheel 88 upon the shaft 21 which meshes with a pinion 89 on the shaft of the roller 90 over which the conveyor belt 84 is trained.

In the operation of the combined stoker and furnace, fuel is delivered into the fuel delivery conduit and the control means is set in accordance with the outside temperature and the switch for the electric circuit is closed.

When one of the contacts 41 of the control mechanism closes the circuit through the conductors 46, 65a, the circuit is then closed through the time switch and through the motor which drives the main crank shaft 30 through one complete rotation and then is stopped by the time switch. During the first half revolution of the crank shaft the grate is stationary and the plunger is moved toward the grate, thereby depositing a charge of the fuel thereon. During the retraction of the plunger the grate is given a partial rotation, thereby presenting a clear space

thereon in front of the discharge opening of the fuel feeding conduit.

The present method of burning solid fuels of any known but widely variable chemical composition and attendant variables comprises the segregation of a predetermined quantity of solid fuel, measured by volume, successively feeding charges of that solid fuel radially upon a cleared section of a circular and perforated grate; igniting each fresh charge of solid fuel by the application of heat and air from the bottom, top and side of the fuel; rotating the grate at predetermined intervals to the end that the coal, without being disturbed, may burn in a series of stages until combustion is complete; timing the movements of the grate so that the coal will be consumed while the grate is making one complete revolution; regulating the timing of the grate movements to permit the use, at will, of the slowest and fastest burning solid fuels or those having a wide range of volatile content; providing automatic draft regulation to supply the quantity of air needed by fuelbeds of varying thickness and burned in different time periods; and removing the ash, automatically, to close the grate to permit the free play of air upon the fuel to be burned.

The electrical control means for the motor and for the damper is set in accordance with the outside temperature and the character of fuel used.

The fuel on the grate continues to burn until each charge has been consumed, leaving only a residue of ashes which encounter the partition or sweep and are swept from the grate, leaving a clear space for a fresh charge.

Having thus described my invention, it is obvious that various immaterial modifications may be made in the same without departing from the spirit of my invention; hence, I do not wish to be understood as limiting myself to the exact form, construction, arrangement and combination of parts herein shown and described, or uses mentioned.

What I claim as new and desire to secure by Letters Patent is:

1. In a combined furnace and stoker, the combination of a fire box having a rotatable grate, a motor, intermittently operated motor starting and stopping mechanism including a circuit breaker in electrical connection with said motor, means driven by said motor and including intermittently operated driving connections to intermittently rotate said grate, a stationary partition extending upwardly and above said grate in a direction radial with respect thereto, said partition functioning to sweep ashes from the grate whereby to provide a clear space on the grate to receive fuel, a fuel delivery conduit having one side wall approximately aligned with said partition and forming the support for said partition, the fuel delivery conduit having a throat opening to said fire box, a ram in said fuel delivery conduit for charging fuel upon said grate in a direction approximately radial thereto, and a driving connection between said ram and motor for intermittently reciprocating said ram in timed relation to the rotatory movement of the grate.

2. In a combined furnace and stoker, the combination of a fire box having a rotatable grate, a motor driven intermittently rotated crank shaft having a crank, drive gearing between said shaft and grate including an intermittently operated driving connection, a fuel delivery conduit having one side wall extending radially with respect to the grate and having a throat opening to the fire

box above the grate, an ash sweeping partition extending upwardly and above the grate, secured to and supported by said side wall and forming a continuation of said side wall, a ram reciprocating in said fuel delivery conduit, and a connection between said ram and crank of the crank shaft arranged to move the ram toward the grate when the latter is stationary.

3. In a combined furnace and stoker, the combination of a fire box having a rotatable grate, a partition extending upwardly and above said grate for sweeping ashes therefrom, whereby to provide a clear space on the grate to receive fuel thereon, a motor driven intermittently rotated crank shaft having a crank, drive gearing between said shaft and grate including an intermittently operated driving connection, a fuel delivery conduit having one side wall extending radially with respect to the grate and forming the support for said partition, said fuel delivery conduit having a throat opening to the fire box above the grate adjacent said partition, a ram reciprocating in said fuel delivery conduit, and a connection between said ram and the crank of the crank shaft for moving the ram toward the grate while the latter is stationary.

4. In a combined furnace and stoker, the combination of a fire box having a rotatable grate, a motor driven intermittently rotated crank shaft having a crank, a beveled gear wheel supporting said grate, a bearing for said beveled gear wheel, an intermittently rotated shaft having a beveled pinion thereon meshing with said gear wheel, drive gearing between said crank shaft and intermittently rotated shaft including an intermittently operated driving connection, a fuel delivery conduit having one side wall extending radially with respect to the grate and having a throat opening to the fire box above the grate, an ash sweeping partition extending upwardly and above said grate substantially in line with said side wall, and being supported by said side wall, a ram reciprocating in said fuel delivery conduit, and a connection between said ram and the crank of the crank shaft for moving the ram toward the grate while the latter is stationary.

5. In a combined furnace and stoker, the combination of a fire box having a rotatable grate, a motor driven intermittently rotated crank shaft having a crank, a beveled gear wheel supporting said grate, a bearing for said beveled gear wheel, an intermittently rotated shaft having a beveled pinion thereon meshing with said beveled gear wheel, a pair of intermeshing gear wheels, one of which is a mutilated gear wheel, a beveled gear wheel connected to the driven one of said gear wheels, a beveled pinion on said intermittently rotated shaft meshing with said last mentioned beveled gear wheel, a fuel delivery conduit having one side wall extending radially with respect to the grate and having a throat opening to the fire box above the grate, a ram reciprocating in said fuel delivery conduit, and a connection between said ram and the crank of the crank shaft for moving the ram toward the grate while the same is stationary.

6. In a combined furnace and stoker, the combination of a fire box having a rotatable grate, a trap door pivotally carried by said grate, an annular track upon which said trap door rides, said track having a downwardly offset portion therein permitting the trap door to drop, motor driven means to intermittently rotate said grate, a stationary partition extending upwardly and above said grate in a direction radial with respect thereto.

to, a fuel delivery conduit having one side wall substantially aligned with said partition and having a throat opening to said fire box, said side wall forming the support for the partition, a ram in said fuel delivery conduit for charging fuel upon said grate in a direction approximately radial thereto, and a connection to said ram and motor driven means for intermittently reciprocating said ram in timed relation to the movements of the grate.

7. In a combined furnace and stoker, the combination of a furnace body, a smoke pipe leading therefrom, a damper in said smoke pipe, a fire box having a rotatable grate, a motor, driving means driven by said motor to rotate the grate, a fuel delivery conduit having a throat opening to the fire box, a ram in said fuel delivery conduit, a connection between said ram and driving means, electrical time control means for starting and stopping the motor, at definite intervals, and manually operable time setting means for changing the lengths of intervals for starting the motor, a member of said time control means having flexible connecting means connected to said damper, whereby the setting of the time control means varies the position of the damper.

8. In a combined furnace and stoker, the combination of a furnace body, a smoke pipe leading therefrom, a fire box having a rotatable grate,

a motor, means driven by said motor to rotate the grate, a fuel delivery conduit having a throat opening to the fire box, a ram in said fuel delivery conduit, a connection between said ram and motor driven means, a damper in said smoke pipe, electrical time control means for starting and stopping the motor and actuating said damper, comprising a motor driven disc having annular rows of contacts, an adjustable contact carrying member having contact fingers for making contact with the contacts of the several rows, said contact fingers comprising terminals in an electric circuit to the motor, operative connections between said contact carrying member and damper, and means to adjust said contact carrying member including an indicating dial.

9. In a combined furnace and stoker, the combination of a furnace body, a smoke pipe leading therefrom, a fire box having a rotatable grate, a motor, means driven by said motor to rotate the grate, a fuel delivery conduit having a throat opening to the fire box, a ram in said fuel delivery conduit, a connection between said ram and motor driven means, electrical time control means for starting and stopping the motor, a damper located in said smoke pipe, and means actuated by said control means for actuating said damper.

GEORGE H. CUSHING.
